UNITED STATES PATENT OFFICE

CHARLES F. ESTWICK, OF ROCHESTER, NEW YORK, ASSIGNOR TO GENERAL RAILWAY SIGNAL COMPANY, OF ROCHESTER, NEW YORK

SIGNALING SYSTEM FOR RAILROADS

Application filed July 12, 1929. Serial No. 377,713.

This invention relates to railroad signaling track circuits and more particularly to alternating current track circuits including two element track relays.

5 Alternating current track circuits, including two element track relays, have many applications, as the local windings of such relays furnish the greater part of the electrical energy, while the track phase windings merely furnish enough energy at a given angle of phase displacement to produce the required torque for controlling the contacts of the track relay. Such an alternating current track circuit may be extremely long as compared to direct current track circuits due to the small amount of electrical energy necessary to be supplied to the track phase winding by the track circuits with which it is associated.

20 As the length of an alternating current track circuit increases, the phase angle of the lagging current in the track phase winding increases correspondingly in respect to the voltage supplied by the transmission line, which may be used as a reference. This phase angle of the track phase current is not determined by the inductance of the circuit alone, but is also dependent upon the resistance of the infinite number of leakage paths 25 provided through the ballast, which leakage paths or circuits are in multiple with the track rails. These conditions being true, if the track circuit is long enough and the ballast resistance is low, the vector of the current in the track phase winding of a particular track circuit may fall within any one of the four quadrants of a vector diagram.

However, with track circuits of practical length and practical ballast conditions, the 40 track phase current seldom lags its voltage reference more than 180° , but if the leads of the track phase winding be reversed, the current vector may still fall in the remaining quadrants. Thus, with this wide variation in phase angle for the lagging track phase winding current, it has been difficult to obtain the proper phase relation between the currents in the track phase and local phase 45 windings in order to maintain the desired

torque and shunting characteristics of the track relay.

It is the purpose of the present invention to set forth a method and means for regulating the phase displacement between the 55 track phase winding and the local phase winding of two element track relays, so that any time the phase displacement can be adjusted to give a maximum amount of torque. Also, the present invention contemplates the 60 use of certain peculiarities of the phase relations of the track phase winding and of the local phase winding of a two element track relay during shunting to produce a maximum shunting efficiency. In other words, a 65 means is to be set forth and a method explained whereby a two element track relay may be deenergized by a shunt having a much greater value of resistance than is the usual practice, due to the phase displacements as obtained by the adjusting means and method of adjustment to be set forth.

70 The present invention, in giving better shunting efficiency, gives a greater assurance of operation of the track relay under both 75 wet and dry weather conditions. Also, as the adjusting means is preferably provided at the location of the track relay, a most convenient means for adjusting and checking the operation of the track relay is thus provided.

80 Other objects, purposes and characteristic features will in part be pointed out and in part be obvious, as a description of the invention is set forth in connection with the 85 accompanying drawings.

In describing the invention in detail, reference will be made to the accompanying drawings, in which:—

Fig. 1 shows an alternating current track 90 circuit as used in general practice;

Fig. 2 shows an alternating current track circuit as included in the present invention;

Fig. 3 shows a vector diagram explanatory of Fig. 1;

Fig. 4 shows a vector diagram explanatory of an ideal modification of Fig. 1;

Fig. 5 shows a vector diagram explanatory of Fig. 2;

Fig. 6 shows a modification of connections 100

for a two element track relay in accordance with the present invention;

Fig. 7 shows a second modification of connections for a two element track relay in accordance with the present invention;

Fig. 8 shows a third modification of connections for a two element track relay in accordance with the present invention.

Referring now to the drawings, Fig. 1 shows an alternating current track circuit having a track transformer T with its primary winding connected to a transmission line and with its secondary winding connected to a track section TK through a variable limiting reactance LR connected in series. A track relay TR is also shown connected to the track section TK at the extreme end from the track transformer T, and associated with said relay TR is a local phase winding LO connected to said transmission line through a local transformer T^1 .

With reference to Fig. 3, let us assume that the voltage applied by the transformer T, is represented by the vector E, and that the current flowing in the track phase winding of the track relay TR is represented by the vector TR^a . As a shunt, having a given maximum value of resistance, which, when placed across the track rails at the relay end of the track section, will drop the contacts of said track relay, the current in the track phase winding of relay TR assumes a value and phase relation represented by the vector TR^b . A circle P may now be constructed with its circumference including the origin O of the vector diagram and the extreme points of the vectors TR^a and TR^b . The circumference of the circle P, defines the limits of the current values for other of shunting resistances, placed across the track rails at a particular point at the relay end of the track circuit.

The current during wet weather conditions is represented by the vector TR^c . When said relay TR is shunted during wet weather conditions, the current in the track phase winding assumes a value TR^d which together with TR^c and the origin O define, and of course fall upon, another circle similar to the circle P, but not shown for the sake of clearness. It is thus seen, that the vector representing the values of current when the relay is shunted, rotates in a clock-wise direction about the origin O of the vector diagram.

As the transmission line furnishes power for both the transformer T and T^1 , the voltage vector E will also serve as a reference for the current vector LO^a representing the current in the local winding LO of the track relay TR. The torque produced for causing the contacts of relay TR to assume energized position is proportional to the values of current flowing in the local phase winding LO and in the track phase winding and directly proportional to the sine of the angle of dis-

placement between the vectors representing the currents, as for example the vectors LO^a and TR^a , values for dry weather conditions. To cause the contacts of relay TR to assume deenergized positions, it is necessary to place a shunt of not more than a given maximum resistance across the track rails at the relay end of the track section to reduce the track phase current to a value TR^b . However, as the vector representing the track phase current rotates in a clock-wise direction, the sine of the displacement angle increases at the same time that the current TR^b decreases so that the resistance value of the shunt to produce a dropping away of the contacts of relay TR must be considerably smaller than if the vector TR^b did not so rotate.

In accordance with the present invention, it is proposed to take advantage of the rotation of the track phase current when shunted, so that it will not be necessary to have a shunt of such a low resistance value to produce a dropping away of the contacts of relay TR. Let us arbitrarily place the vector LO^b as shown in Fig. 4, so that the local phase current LO^b lags the track-phase current TR^a by the same angular displacement that it leads the track phase current in Fig. 3. In this case it is found, that the current, which flows in the track phase winding when the relay TR is shunted, assumes a value TR^x . This current value TR^x (see Fig. 4) is about 200 percent greater than the value TR^b (see Fig. 3), which value TR^x is obtained by a maximum shunting resistance of approximately 200 percent greater resistance than used to obtain the value TR^b .

In accordance with the present invention, means for adjusting the phase displacement between the current in the track phase winding and the local phase winding of the track relay TR, is furnished by a variable condenser C and an adjustable reactance RE as illustrated in Fig. 2, in which a variable limiting resistance LR^1 is substituted for the limiting reactance LR of Fig. 1.

With the condenser C and the reactance RE connected as is obvious from the drawing, it is possible to easily obtain an adjustment of the phase angle of the local phase current in respect to the voltage of the transformer T^1 from its normal angle up to an angle of 180 degrees. Thus, it is seen that if the leads of the local phase winding are reversed, it is further possible with the same apparatus to obtain adjustment of phase relationship through a similar angle placed diametrically opposite.

It is to be noted here, that the use of a limiting resistance LR^1 in place of a limiting reactance causes a very much smaller lag in the phase of the current in the track phase windings of track relay TR, so that for this particular case the results obtained with the arrangement as shown in Fig. 2 are set

forth in Fig. 5, in which the various current values fall within the fourth quadrant of the vector diagram.

With reference to Fig. 5, the vector TR^1 represents the current in the track phase winding during dry weather conditions, the vector TR^2 represents the current in the track phase winding during wet weather conditions, the vector TR^3 represents the current in the track phase winding during shunting with dry weather conditions, the vector TR^4 represents the current in the track phase winding during shunting with wet weather conditions and the vector LO^e represents the current in the local phase winding of the relay TR .

The results obtained by actual experiment as shown in Figs. 3 and 5, have proven that the value of the maximum shunting resistance, at the relay end of the track circuit, for wet weather conditions (see Fig. 5) is about 463 percent greater than the value which would be encountered if the arrangement as shown in Fig. 1 were used, while with dry weather conditions, the value of maximum shunting resistance is about 144 percent greater than with the arrangement used in Fig. 1. It is also pointed out, that as the angle of displacement between the local phase current and the track phase current decreases the maximum shunting resistance value increases. However, in practice it would probably not be advisable to adjust the phase displacement for this maximum usable value of shunting resistance during dry weather conditions as the wet weather conditions would alter the adjustment to cause the track phase vector to rotate beyond the local phase vector, so that the local phase vector would be in a leading position as set forth in explanation of Figs. 1 and 3, also, in the case of a three position relay, such a phase reversal would cause a false indication.

It will be stated here that the conclusions drawn in the preceding paragraph are the result of actual data taken by the inventor. In Fig. 3 the results of the experimental data show vectorially the current value obtained. According to the data obtained the value of resistance required to reduce the relay track phase winding current TR^a to the value represented by vector TR^b equals 0.34 ohms, while the value of resistance necessary to reduce the current represented by vector TR^c to the value represented by vector TR^b equals 0.60 ohms. In Fig. 5 the data obtained under experiments according to the present invention, show the current values obtained vectorially, in which data it was found that a resistance of 0.49 ohms was necessary to reduce the current value represented by vector TR^1 to the value TR^3 , while a resistance of 2.78 ohms was necessary to reduce the current value represented by vector TR^2 to a value TR^4 . It is of course understood that

these specific values of maximum shunting resistance were placed across the track circuit at the relay end, however, similar results are obtained by shunting the track circuit at the other points as the train passes through the block.

With reference to Figs. 6, 7 and 8, three modifications of circuit connections for the track relay TR of Figs. 1 and 2 are shown, with the same pieces of apparatus having like reference characters. These various modifications give desirable phase adjustment for the local phase circuit in a manner similar to that obtained with the circuit arrangement shown in Fig. 2, with each modification having certain characteristic points of utility in obtaining this desired result.

Fig. 6 shows one modification of circuits for a relay having two local windings LO^0 and LO^1 inductively associated with each other. The local winding LO^0 is connected in series with the variable reactance RE to the secondary winding of the transformer T^1 , while the local winding LO^1 is shunted by the condenser C . This arrangement may be designed so that the capacity of the condenser C may be much smaller than in the circuit arrangement shown in Fig. 2, as the resultant capacity effect of the condenser C as transmitted to the circuit including the local winding LO^0 is inversely proportional to the square of the ratio of turns between the two windings LO^0 and LO^1 . Such an arrangement is peculiarly adaptable to the vane type of relay where two local windings are easily incorporated.

Fig. 7 shows a second modification, where the principle of using inductive coupling to reduce the capacity of the condenser C is applied to a relay having but one local winding LO . A transformer T^2 has its primary winding connected across the local winding LO and has its secondary winding shunted by the variable condenser C . The multiple combination of the local winding LO and primary winding of the transformer T^2 is connected in series with the variable reactance RE to the secondary of the transformer T^1 .

Fig. 8 shows a third modification, wherein a fixed resistance R is used in parallel with the local winding LO of the track relay TR . This multiple combination is connected in series with the variable reactance RE to the secondary of the transformer T^1 . The main advantage of this modification is that the necessary adjustment in particular cases may be obtained without the use of a condenser.

It will be noted that with this arrangement, it is possible to obtain an adjustment of the phase angle of the local phase current in respect to the voltage of the transformer T^1 from its normal angle up to an angle of approximately 110 degrees and by reversal of the leads, it is further possible to obtain an

adjustment of phase relationship through such an angle in phase diametrically opposite.

Various means have thus been set forth 5 for regulating the angle of phase displacement between the currents in the local and the track windings of a two element track relay. It has been further shown how this 10 adjustable means may be used to adjust the phase relationships in such a manner as to take advantage of an inherent characteristic 15 of a shunted track section using alternating current for signal purposes.

It is of course understood that the same 15 results could be obtained by adjusting the track phase in relation to the local phase. However, as the procedure is the same, as above, it is not deemed necessary to set forth means whereby this may be accomplished.

20 The present invention having been shown and described in connection with rather specific circuits and devices, it should of course be understood that the various means shown and described are capable of certain modifications 25 and rearrangements without departing from the spirit or scope of the present invention as defined by the appended claims.

What I claim is:—

1. The method, in connection with a track 30 relay having a track phase and a local phase and employed in a track circuit, for improving the relay response to shunting, comprising adjusting the two phase circuits relatively to each other so that the track phase current leads the local phase current under unshunted conditions.

2. The method, in connection with a track 40 relay having a track phase and a local phase and employed in a track circuit, for improving the relay response to shunting, comprising adjusting the two phase circuits relatively to each other so that the track phase current leads the local phase current by an angle not greater than approximately 90 degrees, or such angle plus 180°, whereby shunting of the relay not only decreases the value 45 of the track phase current but also brings it more nearly into phase with the coacting local phase current.

50 3. In combination, a track circuit including an alternating current relay having a track phase winding and a local phase winding, and means relatively varying the constants of the phase circuits to cause the local phase current to lag the track phase current under unshunted conditions.

4. In combination, an alternating current 60 track relay having a track phase winding and a local phase winding, a track circuit including said track phase winding of said alternating current track relay, and means relatively varying the constants of the phase windings to cause the local phase current to lag the track phase current under unshunted 65 conditions.

5. In combination, an alternating current track relay having a track phase winding and a local phase winding, a source of alternating current potential, a track circuit including said track phase winding of said alternating current track relay and said source of alternating current potential, a local phase circuit including said local phase winding of said alternating current track relay and said source of alternating current potential, and means varying the constants of said local phase circuit to cause the local phase current to lag the track phase current by an angle not greater than approximately 90 degrees under unshunted conditions. 80

6. In combination, an alternating current track relay having a track phase winding and a local phase winding, a source of alternating current potential, a track circuit including said track phase winding of said alternating current track relay and said source of alternating current potential, a local phase circuit including said local phase winding of said alternating track relay and said source of alternating current potential, and means varying the constants of said local phase circuit to cause the local phase current to lag the track phase current by an angle of such value, under unshunted conditions, as to allow a shunt of maximum resistance to produce 95 shunting conditions.

7. In combination, an alternating current track relay having a track phase winding and a local phase winding, a source of alternating current potential, a track circuit including 100 said track phase winding of said alternating current track relay and said source of alternating current potential, a local phase circuit including said local phase winding of said alternating current track relay and said source of alternating current potential and means varying the constants of said local phase circuit to cause the local phase current to lag the track phase current with said means including a variable condenser shunted across said local winding and a variable reactance connected in series with said local phase winding shunted by said variable condenser and said source of alternating current potential. 110

8. In combination, an alternating current track relay having a track phase winding and two local phase windings, a source of alternating current potential, a track circuit including said track phase winding of said alternating current track relay and said source of alternating current potential, two local phase circuits inductively associated with each other, and means varying the constants of both of said local phase circuits 120 to cause the currents of the local phases to lag the track phase current with said means including a variable condenser shunted across one of said local windings, and a variable reactance connected in series with the other 130

of said local windings and said alternating current potential source.

9. In combination, an alternating current track relay having a track phase winding and a local phase winding, a source of alternating current potential, a track circuit including said track phase winding of said alternating current track relay and said source of alternating current potential, a local phase circuit including said local phase winding of said alternating current track relay and said source of alternating current potential, and means varying the constants of said local phase circuit to cause the local phase current to lag the track phase current with said means including a transformer with its primary winding connected in multiple with said local phase winding of said alternating current track relay, a variable condenser shunted across the secondary winding of said transformer, a variable reactance connected in series with said local winding and said primary of said transformer connected in multiple, and said source of alternating current potential.

10. The method, in connection with a track relay having a track phase and a local phase and employed in a track circuit, of adjusting the phase relation of the current in the track phase winding to the current in the local phase winding, so that the application of a shunt across the track rails of the track circuit, regardless of the length, at any position on the track, will cause a decrease in the sine of the angle of phase displacement between the currents in the respective phase windings.

11. The method, in connection with a track relay having a track phase and a local phase and employed in a track circuit, of adjusting the phase relation of the current in the track phase winding and the current in the local phase winding, so that the application of a shunt across the track rails of the track circuit, regardless of length, at any position on the track, will cause a change so that variation of phase displacement will be favorable for reducing the torque in the relay.

12. A system, in connection with an alternating current track circuit including a track relay having a track phase and a local phase, of adjusting the phase relation between the track phase current and the local phase current relative to each other so that the application of a shunt across the track rails of the track circuit at any point on the track regardless of the distance between the track relay and its alternating current source, will cause a decrease in the arithmetical value of the sine of the angle of phase displacement between the currents in the track phase winding and the local phase winding.

In testimony whereof I affix my signature.

CHARLES F. ESTWICK.
